(57) **CLAIM**

The ornamental design for an entry phone, as shown and described.

DESCRIPTION

FIG. 1 is a perspective view of an entry phone showing my new design;

FIG. 2 is a front view thereof;

FIG. 3 is a right side view thereof;

FIG. 4 is a left side view thereof;

FIG. 5 is a bottom view thereof; and,

FIG. 6 is a top view thereof.

The broken line showing of the remainder of the entry phone is for illustrative purposes only and forms no part of the claimed design.
